(57) **CLAIM**

The ornamental design for a mixing bottle and closure, as shown.

DESCRIPTION

FIG. 1 is a front view of a bottle and closure incorporating the design of the invention, shown in a closed position;

FIG. 2 is a right-side view thereof;

FIG. 3 is a left-side view thereof;

FIG. 4 is a back view thereof;

FIG. 5 is a top view thereof; and,

FIG. 6 is a bottom view thereof.

The broken lines represent portions of the structure that form no part of the claim.

A bottle and closure for mixing liquids and/or solids and then for dispensing the mixture through a closable aperture in the closure.

1 Claim, 6 Drawing Sheets
